Amusement and gaming machines by gauselmann dated no date given. Found online [Feb. 20, 2017] http://www.gauselmann.de/Portfolio/gaming_machines/*

Primary Examiner — Robert M Spear

Assistant Examiner — Ryan Harvey

(74) Attorney, Agent, or Firm — Ursula B. Day

(57) CLAIM

The ornamental design for a gambling machine, as shown and described.

DESCRIPTION

FIG. 1 is a front elevational view of a gambling machine showing my new design;

FIG. 2 is a rear elevational view thereof;

FIG. 3 is a top plan view thereof;

FIG. 4 is a bottom plan view thereof;

FIG. 5 is a front, right side perspective view thereof;

FIG. 6 is a rear, left side perspective view thereof;

FIG. 7 is a left side elevational view; and,

FIG. 8 is a right side elevational view thereof;
